SASH JACK

Filed May 26, 1928

Eugene J. Clough INVENTOR.
BY *Sayall & Miller*, ATTORNEYS.

UNITED STATES PATENT OFFICE

EUGENE T. CLOUGH, OF OKLAHOMA CITY, OKLAHOMA

SASH JACK

Application filed May 26, 1928. Serial No. 280,694.

My invention pertains to improvements in sash jacks particularly for use in glazing and painting of windows in dwellings and commercial buildings.

The object of my invention is to produce a device of the class described which will be new, novel, strong, substantial, durable, cheap, efficient and of utility; which can be quickly and easily applied for use; which can be quickly and easily dismantled and taken down; which can be compactly and easily packed for shipping; which can be easily and cheaply manufactured and maintained; which will be a great protection to the workmen, and the persons passing under them while they are on the job; which will prevent the spilling of working material and tools from the work scaffolding; which will accomplish all of the purposes for which it is intended.

With these and other objects in view my invention consists in the construction, novel features, and combination of parts herein-after more fully described, illustrated in the accompanying one-sheet drawing, and pointed out in the claims hereto appended; it being understood that various changes in the form, proportion, size, shape, weight and minor details of construction, within the scope of my invention may be resorted to without departing from the spirit or principle of the invention or sacrificing any of the advantages thereof.

The novel features, invention and other objects will be more fully shown in the specification, claims, and accompanying one-sheet drawing, of which,

Figure 1 is a perspective view of the bracket; Fig. 2 is an elevational view showing a bracket attached over a window sill; Fig. 3 is a perspective view showing the brackets attached to a large window; Fig. 4 is a fragmentary perspective view showing an end construction of the bracket.

Like characters of reference designate like parts in all the figures.

In the painting, glazing, and other such work on buildings, such as dwellings, buildings, public buildings, and especially that class known as commercial buildings, it is

unhandy, inconvenient and often times really dangerous to have scaffolding swung on ropes or the like. A strong wind or the accidental slipping of a rope, or the swinging, or tilting of the platform, or board, often precipitates the workmen, and their tools, material and devices with which they are working to the ground; sometimes the wind causes these to swing outward and back against the glass endangering them from cutting and the like. All of these objections are obviated by my invention.

It is my desire to have the drawing and specification to be illustrative and not restrictive and limited.

One embodiment thereof is as follows:

I provide a long first basic platform L-shaped supporting member 1 having a plurality of perforations 2 regularly spaced, on its lower portion being adapted for adjusting the frame supporting members therein; said member has at its outer end an upstanding lug 3 for preventing the working board or platform 16 from sliding off of the outer end of said member; adjacent its other end I provide a re-inforced portion 4 preferably molded or forged thereon said portion having an outstanding threaded portion 5 for receiving a similarly threaded nut 6 for securely fastening to a cross member hereinafter referred to; I also provide an L-shaped lug 7 being adapted to be securely fastened adjacent the said last named end of said platform supporting member 1 on the upper side thereof in an upstanding position being adapted to brace said cross-member 13 and to furnish it with more bearing surface when used in a vertical position with relation to said member 1; I also provide a second member 8 preferably in the form of an angle-iron being adapted to be co-operative at one end, with said member 1 in various angles by being fastened in the perforations therein and a perforation adjacent the end of said member 8 by winged bolts or nuts 9; a third member 10 preferably in the form of an angle-iron having a perforation adjacent each end, one of its ends being co-operative with said member 1 and being adapted to be fastened to perforations therein and by a perforation in

said member 10 and to be held securely in place by winged bolts or nuts 11 the other end of said member 10 being adapted to fit by conjugate perforations with the other end of said member 8, and to be securely held together by winged bolts or nuts 12, or other suitable holding means. It will be observed these may be used at various angles, one of which is shown in Fig. 1 where it is positioned for use with relation to a continuous frame in a commercial building, and another position being shown in Fig. 2 as best adapted for use on a window frame of a dwelling and the like. I also provide a fourth member 13 preferably in the form of an angle-iron having a plurality of perforations 14, the central perforation being adapted for fastening on said threaded bolt portion 5 by holding nut 6, or other suitable means, when used at cross-section with said member 1 when used on commercial buildings, and the like, and the outer perforations for use in fastening said member 13 vertically with relation to said member 1 when used on window frames 15, and the like. It will be observed in this connection said end perforations 14 are removed slightly from the ends for the purpose of giving bracing hold of said member 13 against upstanding L-shaped lug 7.

In operation, it will be observed when applied to a window frame, or the like, as best shown in Fig. 2, member 13 is placed vertically with relation to member 1, its upper end fitting tightly against lug 7, its lower end clamping tightly on the inside of the frame 15 and said member is held securely by bolt 5 and nut 6. Member 1 is positioned horizontally having working boards or platform 16 resting on the top thereof and at right angles thereto; that members 8 and 10 are fastened to perforations 2 in said member 1 intermediate its ends being fastened thereto by winged bolts or nuts 9 and 11; that the other ends of said members 8 and 10 are fastened together by winged bolts or nut 12 their lower ends being adapted to be secured against the outside of said frame 15.

In the operation of the device for use on buildings known as commercial buildings and the like where there is a more or less continuous frame work of windows from top to bottom, member 13 is inserted from the outside through the openings in the metal frame work. This may be more easily done at times by loosening the nut 6 on bolt 5 and changing temporarily the angle of said member 13 then by inserting same through said metal frame and turning member 13 so that it will be at right angles with both member 1 and member 8. Said member 13 will then be against the inside of at least two of the vertical metal frames 17. When desired said member 13 may be made of greater length for more bearing surfaces and for greater holding power. It will also be observed that

for use in such positioning sufficient space is left between said member 13 and member 8 for the insertion therebetween of the horizontal portion 18 of the frame forming divisions. Said member 8 will under such circumstances be vertical with relation to said member 1 and said portions 18. It is desired in such use that at least two of my devices shall be used for properly supporting the working board or platform 16. Said member 8 will be adapted to abut against at least two of such horizontal portions 18, and may, if desired, be made longer to abut a greater number for more resistance power. When so positioned nut 6 is securely tightened on threaded bolt 5 of each of my devices so used, and the working board or platform 16 is then placed upon member 1. After said nut 6 is so positioned I prefer to have a lock washer or nut 6^a placed on said bolt 5 for securely holding said member together. The work of re-positioning same for work in another place is simple, by loosening said nut 6 on said threaded bolt 5 and placing the device as has been above described.

The device can be easily packed and shipped by unfastening the winged bolts or nuts and placing the different members side by side and tying or otherwise fastening them together for shipment.

The member 1 being hereinbefore described as an L-shaped member may also be made in the form of a T-shaped angle iron.

Having thus described my invention what is claimed and desired to be secured by Letters Patent, is:

1. A device of the class described, comprising a first longitudinal member for supporting a working platform, a second and transverse member, said first and second members having a plurality of perforations, a third and vertical member, and a fourth and inclined member, said third and fourth member for supporting said first member each having perforations and being pivotal with each other at their lower ends, each of their upper ends adapted for pivoting with a respective selected perforation in said first member, said second and transverse member adapted for fastening to said first member at right angles and to securely hold said other members to suitable portions of a structure.

2. A device of the class described, comprising a first longitudinal L-shaped angle iron member having perforations, and adapted for holding and supporting a working platform, a second and transverse member having perforations and adapted for fastening on one end of said first member, said first member having on its outer end an upturned lug for holding said working platform thereon, and having its other end reinforced for holding a threaded bolt, said first member and said transverse member adapted for being held together by a threaded bolt

and nut, a third and inclined L-shaped angle iron member having a perforation in its upper end for conjugately and pivotally fitting any selected one of said plurality of perforations in said first member and having a perforation in its lower end, a fourth and vertical L-shaped angle iron member having a perforation in one end, said end adapted to pivotally connect said first member adjacent one of its ends, and having a perforation in its other end adapted to conjugately and pivotally fit the lower end of said third member, said second member having a central perforation adapted for transverse connection with relation to one end of said first member and adapted to be held to said first member by said bolt and nut, an L-shaped upstanding lug secured to the reinforced end of said first member, said second member and said upstanding lug adapted to hold said member securely and rigidly to a fixed portion of a structure.

3. A device of the class described, comprising a first longitudinal L-shaped angle iron member having perforations in one of its webs and an upstanding lip at its outer end adapted for holding and supporting a working platform, and having its other end re-inforced equipped with a screw-threaded bolt and an upstanding L-shaped lug member fastened adjacent said end, a second transverse L-shaped angle iron member having perforations, and adapted for fastening at a selected perforation on said threaded bolt end of said first member, a third L-shaped inclined angle iron member having perforations adjacent each end, one of its ends adapted for pivotally fitting a selected one of said plurality of perforations in said first member, a fourth L-shaped vertical angle iron member having a perforation adjacent each end one of its ends adapted to pivotally connect a selected one of said perforations in said first member and its other end adapted to pivotally connect the second end of said third inclined member, said fourth vertical member and said second transverse member adapted for rigidly gripping the window sill or frame of a building for securing, holding and supporting said first member and said working platform, said second transverse member adapted to be held to said threaded bolt end by a suitable nut and said nut adapted to be locked thereon by a suitable locking nut.

4. A device of the class described, comprising a horizontal member having perforations, a member having perforations and being pivotally secured at a selected one of its perforations to one end of the horizontal member, a vertical member pivotally secured at its upper end to the horizontal member, and an inclined member pivotally secured at its lower end to the lower end of

said vertical member and at its upper end to the horizontal member at a selected perforation of said horizontal member.

5. A device of the class described, comprising a horizontal member having perforations, a second member having perforations and being pivotally secured at a selected one of its perforations to one end of said horizontal member, a vertical member pivotally secured to one end of said horizontal member at a selected perforation of said horizontal member, and an inclined member pivotally secured at its lower end to the lower end of said vertical member and at its upper end to said horizontal member at a selected perforation of said horizontal member.

6. A device of the class described, comprising a horizontal member having perforations, a second member having perforations and being pivotally secured at a selected one of its perforations to one end of said horizontal member, a vertical member pivotally secured to one end of said horizontal member at a selected perforation of said horizontal member, and an inclined member pivotally secured at its lower end to the lower end of said vertical member and at its upper end to said horizontal member at a selected perforation of said horizontal member, said second member disposed at right angles to said horizontal member for clinching said vertical member and said end of said horizontal member to the open framework of commercial buildings, and the like.
